UNITED STATES PATENT OFFICE.

ALBERT BECK, OF CHICAGO, ILLINOIS, ASSIGNOR TO MCGILL METAL PRODUCTS COMPANY, A CORPORATION OF ILLINOIS.

CHANGE CARRIER.

Application filed July 20, 1921. Serial No. 486,106.

To all whom it may concern:

Be it known that I, ALBERT BECK, a citizen of the United States, and a resident of the city of Chicago, in the county of Cook and State of Illinois, have invented certain new and useful Improvements in a Change Carrier; and I do hereby declare that the following is a full, clear, and exact description of the same, reference being had to the accompanying drawings, and to the numerals of reference marked thereon, which form a part of this specification.

This invention relates more particularly to an improved portable change maker wherein all of the coin tubes have the lower ends thereof engaged in a plate casting which is secured to the base plate of the change maker above pivoted ejectors supported on said base plate and operable by levers projecting through apertures in said plate casting to cause ejection of coins from said tubes.

It is an object of this invention to provide a portable change maker wherein one of the coin tubes is longer than the others to hold a greater quantity of coins of a smaller denomination.

It is also an object of the invention to provide a change maker with an auxiliary change maker removably attached to one end thereof by means of the bolt whereon one of the change maker supporting hooks is normally engaged.

Another object of the invention is the construction of a change maker wherein supporting hooks are rotatably and slidably engaged on bolts which hold the upper and lower plates of the device secured in place.

It is a further object of this invention to provide a change maker having gear operated ejectors disposed between base plates and operable by spring controlled triggers to cause the ejection of coins from coin tubes having the lower ends thereof engaged in openings in one of said base plates.

It is an important object of this invention to provide a portable change maker of simple and effective construction wherein removably connected sections are adapted to be supported in position for use by means of hooks slidably and rotatably engaged on clamping bolts which hold the coin tubes clamped between upper and lower plates.

Other and further important objects of

this invention will be apparent from the disclosures in the specification and drawings.

The invention (in a preferred form) is illustrated in the drawings and hereinafter more fully described.

On the drawings:

Figure 1 is a front elevation of a change maker embodying the principles of this invention.

Figure 2 is a section taken on line 2—2 of Figure 1.

Figure 3 is a vertical section taken on line 3—3 of Figure 1.

As shown on the drawings:

The portable change maker comprises a plurality of cylindrical coin tubes 1, 2, 3 and 4 of different sizes adapted to respectively receive quarters, dimes, nickels and pennies. Each of the tubes is provided with a plurality of staggered longitudinal rows of view apertures or slots 5 to permit coins in said tubes to be seen. The coin tube 4 is longer or higher than the other tubes to permit the same to carry a large quantity of pennies necessary for the making of change. The long coin tube 4 has a slotted cap 6 secured on the upper end thereof to permit pennies to be inserted into said tube.

The lower ends of the coin tubes 1, 2, 3 and 4 seat in sockets or rings 7 which form an integral part of an upper base plate 8 having slots or notches 9 in the rear margin thereof. The plate 8 and the rings 7 are made of cast metal to form a unitary or one piece tube retaining plate. The cast plate 8 is rigidly secured upon the top of a metal base plate 10 by screws or rivets 11. Spacers 12 are provided between the base plates 8 and 10 to hold the same spaced from one another.

Pivots mounted between the base plates 8 and 10 below the respective coin tubes are coin ejector rings 13 of different diameters to correspond with the sizes of the tubes. Each ejector ring has teeth 14 integrally formed thereon which mesh with the teeth of a gear segment 15 pivoted between the base plates 8 and 10 similar to the construction illustrated in Figure 2. Each of the gear segments 15 is provided with an opening or slot to receive the lower end of a finger or arm 16 integrally formed at an angle to a trigger or lever 17. Each trigger or lever 17 is provided with a control

spring 18 to hold the same in normal position whereby the gear segment 15 acting on the teeth 14 of an ejector ring holds said ring in normal position below its respective coin tube. Secured at right angles to the rear margin of the lower base plate 10 is a curved upright wall or back plate 19, the ends of which are bent forwardly to form end walls or flanges 20. The upper margin 10 of the back plate 19 is bent forwardly to form a flange 21. Struck inwardly from the back plate 19 are a plurality of lugs 22 for supporting a shaft or rod 23 on which the triggers 17 are pivotally mounted.

15 Secured across the upper ends of the coin tubes 1, 2 and 3 in position to permit the long coin tube 4 to project upwardly therethrough is a cover plate or top 24 which is shaped to close the upper ends of the coin tubes 1, 2 and 3. The cover plate 24 is provided with coin slots 25 of required size to permit coins of the proper denomination to be inserted into the respective coin tubes. Projecting through the rear corners of the 25 base plates 8 and 10 and of the top or cover plate 24 are bolts 26 having nuts engaged on the lower threaded ends thereof below the lower base plate 10. Rotatably and slidably engaged on the bolts 26 are the rings or apertured lugs 27 of supporting hooks 28. The hooks 28 are adapted to be engaged over a belt of a person by whom the portable change maker is used.

An auxiliary or secondary change maker 35 is provided and may be rigidly secured to one end of the main or primary change maker, as illustrated in Figures 1 and 2. The auxiliary change maker is of substantially the same general construction as the main 40 change maker but comprises in this case but a single slotted coin tube 29, the lower end of which is engaged in an opening provided in a ring plate 30 having apertured angle lugs 31 integrally formed on opposite sides 45 thereof and secured on a base plate 32. The base plate 32 is cut away at 33 to afford a coin discharge opening. A slotted cover plate 34 is secured on the upper end of the auxiliary coin tube 29. A flanged ejecting ring 35 adapted to hold a plurality of coins is pivotally mounted on the base plate 32 below the coin tube 29 and below the retaining ring plate 30. The ejector 35 has teeth 14 formed thereon which mesh with the teeth of 50 a gear segment 15 pivotally mounted on the base plate 32. A spring controlled trigger or lever 36 engages the gear segment 15 to permit operation of the coin ejector. The trigger 36 is pivotally mounted on a back 55 plate 37 secured to the base plate 32. The ends of the back plate 37 are bent at an angle and are secured to the side margins of the base plate 32 to form side plates or flanges 38.

60 The top plate 34 and the base plate 32 are

provided with integral apertured lugs 39 through which one of the bolts 26 is adapted to engage to hold the auxiliary change maker connected with the main change maker. The hook 27-28 is removed from said bolt 76 26 and is engaged on a bolt 40 forming a part of the auxiliary change maker. A retaining hook or lug 41 is integrally formed on one of the side flanges 38 to engage over the edge of one of the flanges 20 of the main 75 change maker, as shown in Figure 1. The auxiliary change maker may thus be removably attached to one side of the main change maker to provide an extra coin tube adapted to carry coins such as pennies, a plurality of 80 which may be ejected by a single operation of the trigger 36.

The operation is as follows:

The hooks 28 are rotatably and slidably engaged on the bolts or rods 26 and are 85 adapted to be engaged on the belt of a person who is required to make change. Coins are inserted into the various tubes according to the denominations of said coins. The coins fall by gravity and stack up one upon 90 the other with the lowermost coin of each tube seated within the ejector ring 13. To discharge a coin of a required denomination the respective lever or trigger 17 is depressed thereby causing the arm 16 thereof to swing 95 rearwardly to pivot the respective gear segment. Movement of a gear segment 15 causes the teeth thereof to coact with the teeth 14 of an ejecting ring 13, thereby causing said ring to swing outwardly carrying 100 the lowermost coin outwardly into a position to permit the coin to drop through a cut away portion of the base plate 10 into the hand of an operator. Release of the trigger 17 permits the spring 18 thereof to automatically return the coin ejecting members 105 back into normal position.

Attention is directed to the fact that the lower ends of the coin tubes are held in position by the base rings 7 which form an integral part of the upper base plate 8.

When required the auxiliary change maker may be readily attached to one side of the main change maker by means of one of the bolts 26. The hook 28 of the bolt 26 is 115 removed and engaged on the bolt 40 of the auxiliary change maker. The auxiliary change maker is shaped to conform to the curvature of the main change maker and is rigidly held in place by the bolt 26 and the 120 retaining hook 41 which connects the adjacent end plates 20 and 38, as shown in Figure 1. By depressing the trigger 36 a plurality of coins are ejected from the auxiliary 125 coin tube 29.

Inasmuch as a large number of pennies are required for making change, the coin tube 4 is made longer than the other coin tubes.

It will of course be understood that the 130

auxiliary change maker may have more than one coin tube if necessary.

I am aware that numerous other details of construction may be varied through a wide range without departing from the principles of this invention, and I therefore do not purpose limiting the patent granted otherwise than necessitated by the prior art.

I claim as my invention:

- 10 1. A change maker comprising a frame, coin tubes supported thereon, coin ejecting mechanisms on said frame for discharging coins from said tubes, bolt members removably engaged in said frame, and hooks rotatably and slidably engaged on said bolt members to permit the change maker to be supported in a position for use.
- 15 2. The combination with a main portable change maker, of an auxiliary change maker, bolts removably engaged on said main change maker, hooks adjustably engaged on said bolts for supporting the main change maker in position for use, apertured lugs formed on said auxiliary change maker, a bolt removably engaged on said auxiliary change maker, one of said main change maker bolts adapted to be removed and the hook removed therefrom and placed upon said auxiliary change maker bolt, said removed main change maker bolt adapted to engage said apertured lugs to hold the auxiliary change maker removably attached to said main change maker.
- 20 3. The combination with a main change maker, of an auxiliary change maker, a bolt common to both of said change makers to hold the same connected to one another, bolts on the outer ends of said change makers, and hooks removably and adjustably engaged on said bolts to permit the connected change makers to be supported in position for use.
- 25 4. The combination with a large change maker and a small change maker, a bolt supported on said large change maker, a

hook adjustably engaged thereon, a second bolt on said large change maker, a hook adapted normally to be engaged on said second bolt to permit the large change maker to be supported in position for use independently of the small change maker, and a third bolt on said small change maker, said second bolt adapted to be removed and the hook taken therefrom and then remounted to connect the small change maker to said large change maker, said removed hook adapted to be adjustably engaged on said third bolt to permit the connected change makers to be supported in position for use.

5. A change carrier comprising a base section, coin ejecting mechanisms mounted therein, means for operating the same, a top section having openings therein, a plurality of coin tubes between the base section and said top section, members connecting the base section and said top section to hold the coin tubes in place, and supporting members for the change carrier movably engaged on said connecting members.

6. A change carrier comprising upper and lower plates, coin tubes engaged therebetween, bolts for connecting said plates to hold the coin tubes in place, and supporting members for the change carrier rotatably and slidably engaged on said bolts.

7. A change holder comprising a main change carrier, an auxiliary change carrier pivotally supported thereon, and means rotatably and slidably mounted on said main change carrier and on said auxiliary change carrier to permit the change holder to be supported in position for use.

In testimony whereof I have hereunto subscribed my name in the presence of two subscribing witnesses.

ALBERT BECK.
